CIRCULAR HOSIERY KNITTING MACHINE

Harry E. Katzenmoyer, Reading, Pa., assignor to
Chas. Chipman's Sons Co., Inc., New York,
N. Y., a corporation of New York

Application February 13, 1935, Serial No. 6,278

6 Claims. (Cl. 66—41)

This invention relates to circular hosiery knitting machines; and it has reference more particularly to circular hosiery machines such as disclosed in U. S. Patent No. 1,282,958 granted to 5 R. W. Scott on October 29, 1918, with automatic mechanism for forming closed welts at the tops of the stockings.

The chief aim of my invention is to make it possible to produce on circular knitting machines of the kind specifically referred, what are known as "ringless" stockings, wherein, instead of a single main or body yarn, several such yarns of like gauge are employed in the knitting, with the courses respectively formed from them succeeding each other in a predetermined regular order, so that irregularities in the yarns are distributed with preclusion of unsightly horizontal bands or "rings" in the fabric.

The foregoing objective I attain in practice, as 20 hereinafter more fully set forth, through provision amongst other things, of an auxiliary feed to serve a second main yarn of the same gauge, color and material as the first main yarn, to the needles at a point circumferentially spaced from 25 the usual main yarn feed of the machine, and an auxiliary cam for retracting the web holders of the machine at the auxiliary feed; and by utilizing one of the needle actuating cams of the automatic welting mechanism as an auxiliary 30 stitch cam to knit the second main yarn served to the needles by the auxiliary feed aforesaid.

Other objects and attendant advantages will be manifest from the detailed description following of the drawings, wherein Fig. I is an elevation of 35 a circular stocking knitting machine with automatic welt forming mechanism and ornamental splicing control mechanism, conveniently embodying my invention, portions of the machine having been broken away to expose important 40 details which would otherwise be hidden.

Fig. II is a fragmentary plan view of the machine taken as indicated by the arrows II—II in Fig. I.

Fig. III is a sectional view of the machine 45 taken as indicated by the arrows III—III in Fig. II.

Fig. IV is a view showing the connections by which the auxiliary cam for the web holders is controlled, the web holder cam ring having been 50 turned into a vertical plane for convenience of illustration.

Fig. V is a fragmentary view corresponding to Fig. IV showing the auxiliary sinker cam in retracted or idle position.

55 Fig. VI is a fragmentary view of the machine

partly in elevation corresponding to Fig. I and partly in axial section.

Fig. VII is a fragmentary detail sectional view taken as indicated by the arrows VII—VII in Fig. II, and drawn to a larger scale. 5

Fig. VIII is a view looking as indicated by the arrows VIII—VIII in Fig. VII.

Fig. IX is a diagrammatic view showing the needles, the needle jacks and the needle actuating cams in linear development together with the 10 auxiliary feed and certain special cams provided in accordance with my invention for the purpose of ringless knitting.

Fig. X is an elevation of welt top ringless stocking such as may be produced in a circular welting 15 knitting machine modified in accordance with my invention.

Fig. XI shows the texture of the fabric of the stocking within the dotted rectangle XI in Fig. X; and 20

Fig. XII is a diagrammatic view showing how the two main yarns are concurrently fed during the knitting of the body portion of the stocking.

With more detailed reference to these illustrations, 1 designates the needle cylinder which is 25 suitably supported for rotation in the bed plate 2 of the machine and which is rotated or oscillated as required in making seamless stockings, by a bevel gear wheel 3 on the main shaft 4 of the drive mechanism of the machine. Secured to the 30 needle cylinder 1 is the dial ring 5 for the web holders 6 (Fig. VI) which coat individually with the needles 7 during the knitting. The web holders 6 are actuated by a cam groove 8 in a cap ring 9 which rests upon the dial ring 5 and which 35 has adjustable stop screws 10 (Figs. IV and V) to engage with a post 11 on the bed plate 2. The latch guard ring 12 of the machine is swingable up and down about a pivotal connection 13 with another post 14 on the bed plate 2 at a point 40 diametrically opposite the post 11. Fulcrumed for independent pivotal movement on a transverse pin 15 in upstanding lugs 16 of the latch guard ring 12 are the usual yarn feeds which include a main yarn feed finger 17 and a splicing 45 yarn feed finger 18, as well as a heel and toe yarn feed finger not illustrated, these several feed fingers being individually sprung pressed and controlled through vertical thrust rods from the pattern drum 19 of the machine. The thrust rods for the main and splicing yarn feeds 17 and 18 are indicated respectively at 20 and 21 in Figs. I and III. As usual in knitting machines of this 50 type, the pattern drum 19 is intermittently rotated through a train of gears 22 (Fig. I) under 55

governance of the measuring chain 23. An inwardly reaching bearing bracket 24 rotatively supports in axial alignment with the needle cylinder 1, the shaft of a circular dial 25 affording radial guidance for the loop holding hook instrumentalities 26 which cooperate with alternate knitting needles 7 during the formation of an initial or set-up course for the stocking welt and again in closing the welt subsequently. The dial 10 25 is rotated in unison with the needle cylinder 1 through drive connections including a bevel gear 27 (Fig. III) on the main shaft 4 of the machine, said bevel gear meshing with a bevel pinion 28 on a vertical shaft 29 which is supported for rotation in the bed plate 2. By means 15 of a bevel pinion 30 at the top end of the shaft 29 motion is transmitted to a bevel gear 31 on a horizontal shaft 32 which is suitably journaled on the latch guard ring 12 and from which motion 20 is in turn transmitted, through another bevel gear couple 33, 34 (Fig. VI) to the shaft of the dial 25. During certain rotations of the dial 25, the loop holding instrumentalities 26 are actuated by retractable cams (not illustrated) on a cam plate 35 fixedly supported in coaxial relation to 25 said dial by the bracket 24 aforementioned.

The needle actuating cams of the machine include the stitch cams 36 and 37 which are symmetrically allocated on the cam shell 38 at opposite sides of the top and bottom center cams 39 and 40, and a switch cam 41 by which the usual long butt needles of the series 7 are raised to the idle level as required during toe and heel pocket knitting, and again lowered into action 35 when round and round knitting is resumed. The machine is also provided with a pair of lifting pickers 42 and 43, and a drop picker 44, all of which function in the known manner during the knitting of heel and toe pockets.

40 For the purpose of effecting a subdivision in the needles 7 during the formation of a setting up course at the commencement of a stocking and again during welt closing, the needle cylinder 1 is fitted with lifting jacks 45 whereof there 45 is one for every other needle. These jacks 45 are actuated by a jack cam which is indicated at 46 in Fig. IX. In addition, the machine is fitted with a transfer cam 47, a dividing cam 48 and a depressing cam 49, all of which are instrumental 50 in causing the two groups of the needles subdivided by action of the jacks 45 to take different courses through the knitting cams 36, 37, 39 and 40 as they pass the main yarn feed 17 in the well known manner. The transfer cam 47 is secured 55 to the inner end of a slide 50 capable of movement radially of the needle cylinder in a guide 51 on the bed plate 2, see Figs. II and VII. The position of the transfer cam 47 is controlled by a cam segment 52 on the pattern drum 19 of the machine through a vertical thrust rod 53 with a bevel projection 54, and a horizontal lever 55 which is centrally fulcrumed at 56 on the bed plate 2 and whereof one end lies in the path of the bevel on said thrust rod. The other end of the lever 55 bears against the outer end of the slide 50, which latter, as shown in Fig. VIII, is 60 yieldingly urged outward of the guide by a spring pressed plunger 57. The depressing cam 48 is carried by a separate slide 58 in the guide 51, and is shifted in and out concurrently with the transfer cam 47. The dividing cam 49 is carried by a slide 59 with radial guidance in another fixed bracket 60 on the bed plate 2, said slide being yieldingly urged outward of the needle cylinder 65 by a concealed spring. As shown in Fig. II, the

slide 59 carrying the cam 49 contacts at its outer end with one end of a lever 61 which is centrally fulcrumed at 62 on the bed plate 2 and with the opposite end thereof lying in the path of a beveled lug 63 on a thrust rod 64 also controlled from the pattern drum 19 of the machine. 5

For the purpose of determining an ornamental configuration for the spliced portions of the stocking, the machine is provided with control mechanism for varying the feeding periods of the splicing yarn feed finger 18 during these phases of the knitting. This splicing control mechanism comprises a rotary cam 65 which is secured to the main shaft 4 of the machine, and which acts upon a roller 66 at the end of an arm 67 free on fulcrum pin 68 projecting from the frame of the knitting machine. Also free on the fulcrum pin 68 is a second arm 69, which, at the top, has a pivotal connection 70 with one end of a horizontal bar 71. At its opposite end, the bar 71 carries a pin 72 that rides the periphery of a disk cam 73 on a shaft 74 suitably journaled in the machine frame, said bar being longitudinally slotted at 75 for support and guidance to endwise movement by the shaft. A helical spring 76 in tension 20 between anchorages on the arm 67 and the bar 71, serves to hold the roller 66 and the pin 72 respectively in yielding contact with the rotary cams 65 and 73. Centrally fulcrumed to the bar 71 at 77 is a horizontal lever 78, which, at one 30 end, has a downward projection 78a adapted to be wiped by a cam lug 79 on the arm 67, and which, at the other end, bears on one end of a cross arm 80. As shown, this cross arm 80 is pivoted at the center on a fixed screw 81, and has 35 its other end underreaching a projection 82 on the thrust bar 21 for the splicing yarn feed 18. The shaft 74 carrying the disk cam 73 has mounted thereon a ratchet wheel 83, which, during the splicing of the high heel of a stocking, is picked 40 two teeth at a time by a pawl 85; while, during the splicing of the sole of a stocking; said ratchet wheel is picked one tooth at a time by another pawl 86. Both pawls 85 and 86 are given the required picking movements by virtue of pivotal 45 connection respectively at 87 and 88 with the arm 67 at different distances from the fulcrum axis 68. Normally, the pawl 85 is held raised out of contact with the ratchet wheel 83 by a pin 89 on a thrust bar 90 controlled from the pattern 50 drum 19; while the other pawl 86 reciprocates idly upon a blank spot 91 on the ratchet wheel. During operation of the mechanism, as the disk cam 73 is intermittently rotated in the direction of the arrow thereon by either of the pawls, the bar 71 is gradually moved endwise, with attendant shifting of the fulcrum 77 of the horizontal lever 78. As a consequence, the lug 78a at the right hand end of the horizontal lever 78 is moved closer to or farther away from the cam 60 lug 79 on the roller arm 67. Thus, through the cross lever 80 and the thrust rod 21, the splicing yarn Y² (Figs. I and XI) is lifted out of action 65 for correspondingly greater or longer intervals during successive courses of the splice knitting. To start the control mechanism for heel splicing, the pawl 85 is permitted to drop into engagement with the ratchet wheel 83 under control of the pattern drum 20 through the thrust bar 90. Starting of the mechanism for instep splicing is 70 effected by an initial shift of the ratchet wheel 83 to bring the blank idling spot 91 of the latter past the pawl 86. This may be effected by momentarily bringing the pawl 85 into action, or by any other suitable means. 75

In order to adapt a circular knitting machine such as has been described for ringless knitting, I have made the provisions which are about to be described. Mounted for independent movement upon the pivot pin 15 for the usual yarn feed fingers 17 and 18 is an auxiliary feed finger 93 which serves to feed an additional main yarn Y' of the same gauge, quality and color as the usual main yarn Y to the needles 7 at a point directly above the transfer cam 41, which latter I utilize as an auxiliary knitting cam, the auxiliary main yarn Y' so fed being subject to a regulatable tension device, see Fig. I, consisting of a pair of friction disks 92 free on a fixed stud 94 and subject to a light compression spring 95 whereof the pressure is adjustable by means of nuts 96 engaging screw threads on the stud. When not needed, the auxiliary main yarn feed finger 93 is held in the dotted line position shown at 93' in Fig. IX by a helical spring 97 (Fig. I) at an elevation which will insure its being cleared by the long butt needles of the series 7 when the latter are raised to idle level during heel and toe pocket knitting. The auxiliary main yarn feed finger 93 is permitted to drop into action under control of the pattern drum 19, which to this end is provided with a cam segment 98 to actuate a vertical thrust rod 99 whereof the upper end is bent at 99a to underreach the tail 93a of said auxiliary main yarn finger as shown in Fig. I. For a reason later on explained, the cam segment 98 of the drum 19 is formed at its leading end with a step or shoulder 98a.

In order that the size of the loops formed from the auxiliary main yarn Y' may be made to correspond exactly with the loops formed from the main yarn Y under the action of the knitting cams, I have made provisions whereby the transfer (auxiliary stitch) cam 41 can be adjusted vertically. As shown in Figs. VII and VIII, the slide 50 carrying the transfer cam 41 is urged upwardly in the guide 51 by a spring pressed plunger 100 so as to bear against a stop plate 101 which is held against displacement endwise by an upwardly projecting stud 102 engaging an aperture 103 in the top 51a of said guide. As shown, the top plate 101 in turn bears against adjusting screws 105 and 106 which pass down through tapped apertures in the top 51a of the guide 51. The screw 105 is securable in adjusted positions by means of a set screw 107 engaging it from one side, while a jam nut 108 serves as a fixing means for the other adjusting screw 105. Thus by adjusting either the auxiliary main yarn tensioning means 92 or the transfer cam 41, or both, it is possible to make the fabric loops drawn from the auxiliary main yarn Y' exactly equal in size to those formed from the usual main yarn Y.

A further feature novel to my invention resides in a cam 110 (Figs. I, II, III and IX) for raising the needles 7 to clear their latches as they approach the auxiliary main yarn feed 93. As shown, this latch clearing cam 110 occupies a vertical recess 111 in the cam shell 38 of the machine immediately beneath the drop picker 44. A pin 112 projects outwardly from the cam 110 through a vertical slot 113 in the cam shell 38, and overlies a finger 115 which is fulcrumed for up and down movement in a bearing 116 secured to the top of the bed plate 2. Extending laterally from the outer end of the axis 115a of the finger 115 is an arm 117 which is engaged by one end of a comparatively strong helical spring 118, the other end of said spring being connected

to an anchorage screw 119 threaded into the circumferential face of the bed plate 2. A lighter spring 120 held in place on the outer side of the cam shell by a screw 121, keeps the stud 112 of the latch clearing cam 110 yieldingly in contact with the finger 115. Another finger 122 with an axis portion 122a journaled in the post 11 bears upon the finger 115 from above, and at the outer end of its axis portion has a short arm 123 overlying the top end of a vertical thrust rod 124 with guidance for up and down movement in the bed plate 2 of the machine. The bottom end of the thrust rod 124 rests upon one end of a lever 125 which is centrally fulcrumed on a fixed screw stud 126, and upon the other end of said lever rests the contiguous end of a cross arm 127. This cross arm 127 is likewise centrally fulcrumed on a fixed screw 128, see Fig. I, and has its opposite end pivotally connected at 129 to the top of another vertical thrust bar 130 which is acted upon by the cam segment 131 on the pattern drum 19. Near its bottom end, the thrust bar 130 has a slot connection with a guide screw 132 fixed in the frame of the machine.

A further innovation resides in an auxiliary cam 133 (Figs. IV and V) for retracting the web holders 6 at the region where the auxiliary main yarn Y' is served to the needles 7 by the auxiliary web feed finger 93. As shown, the auxiliary web holder retracting cam 133 is pivoted at 134 to the web holder cap ring 9, and has a stud 135 which reaches up through a notch 136 in said ring for engagement in one extremity of a bell crank lever 137. This bell crank lever 137 is fulcrumed at 138 to the top of the web holder cap ring 9, and to the end of its other extremity is pivotally connected a coupling rod 139 which passes through an apertured swivel stud 140 at the upper end of a cam lever 141 fulcrumed at 142 to a fixed bracket 143 on the bed plate 2, see Fig. II. A helical spring 144 surrounding the projecting end of the connecting rod 139 and in compression between the stud 140 and a collar 145 adjustably set upon said rod, permits the parts to yield if necessary when the auxiliary web holder retracting cam 133 is moved from the inoperative position shown in Fig. V, to the operative position shown in Fig. IV. Adjacent its fulcrum 142, the cam lever 141 has a laterally projecting curved heel 141a engaged by the top end of another vertical thrust rod 146 whereof the lower end lies in the path of the cam segment 147 on the pattern drum 19. As long as the thrust rod 146 rides on the cam segment 147, the supplemental web holder retracting cam 133 will be held in its active position as shown in Fig. IV.

Instead of being made in one piece as ordinarily, the jack cam 46 is, in accordance with my invention, constructed with a retractable section 46a which is secured to a slide 148, see Fig. II, having guidance radially of the needle cylinder 1 in still another fixed guide bracket 149 on the top of the bed plate 2. A finger spring 150 engaging a stud 151 on the slide 148 tends to keep the outer end of the latter in contact with one end of a horizontal lever 152 which is pivoted at an intermediate point on a fixed fulcrum screw 153 engaged in a bracket 154 on the bed plate 2. The opposite hook end of the horizontal lever 152 is adapted to be engaged by the beveled projection 155 of a vertical thrust bar 156 (Figs. III and IV) whereof the lower end lies in the path of the cam segment 157 on the pattern drum 19. With this arrangement it will be evident that the movable section 46a of the jack cam 46 is held advanced

in its active position as long as the thrust bar 156 rides the cam segment 157 of the pattern drum. The operation of the machine is as follows: At the beginning of the stocking a subdivision is effected in the needles 7 by the concerted action of the jacks 45 under the influence of the jack cam 46 and the depressing cam 49 for the purpose of producing a setting up course from the main yarn Y fed by the main yarn feed finger 17 (which 10 alone is in action at this time). In a subsequent course alternate needles form their loops over the hooks of the loop holding instrumentalities 26 in the dial 25. The instrumentalities 26 are then retracted to hold the loops and the depressing cam 15 49 withdrawn to permit actuation of all the needles in the normal way by the knitting cams to produce the fabric for the welt W of the stocking shown in Fig. X. The transfer cam 47 is then placed into action and the hook instrumentalities 20 26 again actuated to replace the held loops upon the needles from which they were originally taken, thereby closing the welt along the line A—A in the manner well understood in the art. Instead of being withdrawn as ordinarily at this 25 stage of the operation, the transfer or auxiliary stitch cam 47 is left in action. During the knitting of a few plain fabric courses, the movable section 46a of the jack cam is retracted from active position so that all the needles 7 may pass beneath the transfer or auxiliary stitch cam 47. Retraction of the auxiliary jack cam section 46a is effected under the influence of the spring 150, as the thrust bar 156 drops from the cam segment 157 of the pattern drum directly onto the surface 30 of said drum to the position shown in Fig. III. At about the time that the latter event occurs, a shift of the pattern drum 19 causes the shoulder 98a of the cam segment 98 to be advanced beneath the thrust rod 99 whereby the auxiliary main yarn feed finger 13 is moved from its high position indicated at 93' down to the intermediate position shown at 93" in readiness to be placed into action. Also concurrently with the last described occurrences, the latch clearing cam 110 is raised 35 to its operative position by engagement of the cam segment on the drum 19 with the thrust rod 130, and the auxiliary web holder retracting cam 133 placed in its operative position by engagement of the thrust rod 146 with the cam segment 147 on said pattern drum. Slightly later during 40 another shift of the pattern drum 19 the high portion of the cam segment 98 advances beneath the thrust rod 99 whereby the auxiliary main yarn feed finger 93 is moved into feeding position as 45 shown in full lines in Fig. IX, the timing being such that the needle first to have its latch cleared by the cam 110 arrives at said auxiliary feed finger just as the latter is fully lowered to preclude dropping of the loops of the main yarn held 50 on the needles. From then on, both the main and the auxiliary main yarn are served to the needles concurrently after the manner conventionally shown in Fig. XII to produce ringless fabric down through the leg portion L of the stocking. When 55 the line B—B, Fig. X, is reached, the splicing yarn feed finger 18 is released for action under governance of the pattern drum 19, and the pawl 85 at the same time permitted to drop into engagement with the ratchet wheel 83 of the splicing 60 control mechanism, also under governance of the pattern drum. By action of the control mechanism, the splicing yarn finger 18 is moved into action for progressively increasing periods during the knitting of successive courses of the 65 fabric with formation of the ornamentally-con-

figured high heel at N, the ratchet wheel 83 being picked two teeth at a time as hereinbefore described, to compensate for the additional main yarn Y' fed to the needles by the feed finger 93. The result of the splicing action is diagrammatically shown in Fig. XI from which it will be observed that the loops of the splicing yarn Y' are coincident only with the loops of the usual main yarn Y. When the line C—C (Fig. X) where the knitting of the heel pocket H is to be commenced, the splicing yarn feed finger 18 is withdrawn from action, the pawl 85 lifted from engagement with the ratchet wheel 83 of the splice control mechanism incident to another shift of the pattern drum 19, and the latch clearing cam 110 lowered as the cam segment 131 (Fig. I) of said pattern drum advances beneath the thrust bar 130. Also at the same time, the transfer or auxiliary stitch cam 47 is withdrawn, the auxiliary main yarn feed finger 93 lifted out of feeding position, and the auxiliary web holder retracting cam placed in inactive position by substantially simultaneous dropping of the corresponding thrust bars 53, 99 and 146 off the cam segments 52, 98 and 147 respectively of the pattern drum 19; while the switch cam 41 is brought into action to raise the long butt needles into idle level in preparation of the knitting of the heel pocket H which takes place in the usual manner, the heel pocket being knit with heel yarn served by another feed finger (not illustrated) which is substituted for the main yarn finger at the time the machine enters into a reciprocatory phase of operation. After completion of the heel H, the long butt needles are lowered to active level by the switch cam 41 as the 35 machine is restored to rotary operation, and the main yarn and splicing yarn fingers 17 and 18 are again placed in action with attendant retraction of the heel yarn finger aforementioned, and the splicing control mechanism at the same time 40 restored to activity. Then, by round and round knitting, the instep I of the stocking is produced. While in the present instance the ringless knitting is terminated at the line C—C, it is obviously possible within the scope of my invention, to 45 provide duplicate cam control segments on the pattern drum 19 similar to those hereinbefore described whereby the transfer cam 47, the latch clearing cam 110, and the auxiliary main yarn feed finger 93 and the auxiliary web holder re- 50 tracting cam 133 may be replaced in action after knitting of the heel pocket H to produce a ringless knit instep. After completion of the instep I, the machine is once more set into oscillation to produce the stocking toe T in the usual way from 55 the heel yarn, the feed finger for which is substituted for the main yarn feed as the latter oscillatory phase of the machine is initiated.

Having thus described my invention, I claim:

1. A circular stocking knitting machine comprising a series of needles and cooperating web holders, a main yarn feed, knitting cams for actuating the needles to draw fabric loops from the main yarn, automatic welting mechanism with cams circumferentially spaced from the knitting cams adapted to actuate the needles during the formation of setting up courses and in closing of the welts of the stockings and a splicing yarn feed; in combination with means for adapting the machine to ringless knitting including an auxiliary feed for separately feeding, during each rotation of the needle cylinder incident to the knitting of the stocking body, an auxiliary yarn corresponding in gauge, quality and color to the main yarn for formation into fabric loops by the 75

needles while the latter are actuated by one of the cams of the welting mechanism, and means for controlling said splicing yarn feed so that the splicing yarn is interknitted with only one of the two main yarns in the reinforced portions of the stocking.

2. A circular stocking knitting machine comprising a series of needles and cooperating web holders, a main yarn feed, knitting cams for actuating the needles to draw fabric loops from the main yarn, automatic welting mechanism with cams circumferentially spaced from the knitting cams, including a transfer cam influential upon the needles during the closing of the stocking welts and a splicing yarn feed; in combination with means for adapting the machine to ringless knitting including an auxiliary feed for separately feeding, during each rotation of the needle cylinder incident to the knitting of the stocking body, an auxiliary yarn corresponding in gauge, quality and color to the main yarn for formation into fabric loops by the needles while the latter are actuated by the transfer cam aforesaid of the welting mechanism, and means for controlling said splicing yarn feed so that the splicing yarn is interknitted with only one of the two main yarns in the reinforced portions of the stocking.

3. A circular stocking knitting machine comprising a series of needles and cooperating web holders, a main yarn feed, knitting cams for actuating the needles to draw fabric loops from the main yarn, means for retracting the web holders in the region of the main yarn feed, automatic welting mechanism with cams circumferentially spaced from the knitting cams and including a transfer cam adapted to influence the needles during the closing of the stocking welts and an auxiliary yarn feed; in combination with means for adapting the machine to ringless knitting including an auxiliary feed for separately feeding, during each rotation of the needle cylinder incident to the knitting of the stocking body, an auxiliary yarn corresponding in gauge, quality and color to the main yarn for formation into fabric loops by the needles while the latter are actuated by the transfer cam aforesaid of the welting mechanism, an auxiliary cam for retracting the welt holders at the auxiliary yarn feed, a cam for actuating the needles to clear their latches as they approach the auxiliary main yarn feed, and means for withdrawing from action the transfer cam, the auxiliary web holder retracting cam and the needle latch clearing cam upon change of the machine from its rotary to its oscillatory phases to knit the heel and toe pockets of the stockings, and means for controlling said auxiliary yarn feed so that the

auxiliary yarn is interknitted with one of the main yarns in the reinforced portions of the stocking.

4. A circular stocking knitting machine in accordance with claim 1, including in addition, means for controlling the activity of the splicing yarn feed and for varying the periods of its activity during successive rotation of the needle cylinder in forming ornamentally configured spliced areas above the heel and in the instep portions of the stockings, and means for actuating the splicing yarn control means in such manner as to compensate for the added auxiliary main yarn in the knitting.

5. A circular stocking knitting machine in accordance with claim 2, including means whereby the transfer cam can be adjusted vertically for the purpose of securing uniformity between the fabric loops respectively formed from the auxiliary and main yarns.

6. A circular stocking knitting machine comprising a series of needles and cooperating web holders, a main yarn feed, knitting cams for actuating the needles to draw fabric loops from the main yarn, means for retracting the web holders in the region of the main yarn feed, lifting jacks associated with alternate needles, automatic welting mechanism with a cam to actuate the jacks for the purposes of effecting a subdivision in the needles during the formation of setting up courses and during closing of the stocking welts, a transfer cam adapted to influence the needles during the closing of the stocking welt and a splicing yarn feed; in combination with means for adapting the machine to ringless knitting including means for removing the jack cam from action upon the completion and closing of the stocking welts, an auxiliary feed for separately feeding, during each rotation of the needle cylinder incident to the knitting of the stocking body, an auxiliary yarn corresponding in gauge, quality and color to the main yarn for formation into fabric loops by the needles while the latter are actuated by the transfer cam aforesaid of the welting mechanism, an auxiliary cam for retracting the web holders at the auxiliary yarn feed, a cam for actuating the needles to clear their latches as they approach the auxiliary yarn feed aforesaid, and means for withdrawing from action the transfer cam, the auxiliary web holder retracting cam and the needle latch clearing cam upon change of the machine from its rotary to oscillatory phases to knit the heel and toe pockets of the stockings, and means for controlling the splicing yarn feed so that the splicing yarn is interknit with one of the main yarns in the reinforced portions of the stocking.
